UNITED STATES PATENT OFFICE.

JAMES P. DOVEL, OF BIRMINGHAM, ALABAMA.

METHOD FOR THE PROTECTION OF BLAST-FURNACE JACKETS.

Original application filed September 17, 1923, Serial No. 663,283. Divided and this application filed March 16, 1928. Serial No. 262,268.

My invention relates to blast furnaces and has for its object the provision of a process for producing an agglomerate lining for such furnaces.

5 A further object of my invention is to provide a process for producing and maintaining a lining for a blast furnace comprised of agglomerated refractory particles from the stock and self replaceable in operation of the 10 furnace.

The invention herein described is a division of my application for Letters Patent, Serial No. 663,283, filed September 17, 1923.

Heretofore, in this art, it has been the practice to incorporate in the refractory brick lining of the furnace above the bosh a number of cast iron coolers connected up with a source of circulating water, and it was the purpose and function of these coolers to protect the surrounding brick work in the lining from temperatures that would melt the same, and thus the theory was that these coolers would greatly increase the life of the lining. In practice, however, experience has shown 25 that when the lining has worn away so as to expose these coolers, either from abrasion, heat, or chemical action, the coolers would invariably burn out or fall out by reason of inadequate support and thereupon the furnace man was subjected to expense and trouble of relining his furnace. So far as I 30 am aware, no practical provision has heretofore been made for the removal and replacement of cooling blocks in the brick lining 35 above the mantel, thereby making it possible to repair the furnace.

In the operation of certain blast furnaces under my charge I experienced an abnormally rapid destruction of the lining in a zone 40 extending about twenty feet above the bosh. Throughout a large portion of this zone, which was water cooled, the brick lining was entirely burned away and the shell would have been exposed to the raw stock and the intense heat except for a thin lining of an 45 agglomerate material which formed on the shell and supported the brick lining above it. After an examination of this condition I conceived the idea of building up within the furnace an agglomerate lining composed entirely of slag and stock materials by the introduction through the shell of cooling elements 50 preferably in the form of standard bronze bosh blocks, and by arranging these in such 55 relation that the partially molten metal and

fine particles of the stock would agglomerate and build up on and about same until a complete protection or lining having approximately the thickness of the original lining would cover the jacket throughout the zone 60 under treatment, or the whole jacket, were it desired to provide the original lining by this method.

My invention therefore comprises the method of utilizing such blocks so as to build 65 up by an agglomeration of stock a protecting lining in the furnace jacket. The lining so built up within the furnace in actual practice has proved more effective than the brick lining and far less subject to deterioration. 70

The method of practicing my invention and the preferred embodiment of the means to that end will be best understood by reference to the accompanying drawings, which 75 form a part of these specifications, and in which:—

Fig. 1 is a partial elevation and partial section through a furnace equipped with my invention.

Fig. 2 is an enlarged side elevation of a 80 cooling block with its individual mounting frame mounted in the jacket, and

Fig. 3 is an end elevation of Fig. 2, showing the block mounted in an individual frame.

Similar reference numerals refer to similar parts throughout the drawings. 85

In the practice of my invention I propose to protect the jacket of any type of blast furnace above its bosh, by means which will cause the building up of a lining by an agglomeration of materials charged in the furnace, which lining will cover the exposed jacket walls to such an extent and in such manner as to protect them even more effectively than they are at present protected by the brick, 95 and it is within the scope of my invention that the original lining for the furnace may be so created by the utilization of my method and process, as well as that an existing lining may be repaired and replaced in part whenever it 100 has failed.

To illustrate the practice of my invention I have shown in the accompanying drawings a metallurgical blast furnace having a bosh 1, and above this the usual metal jacket or shell 2, which in the drawings is shown as having been previously lined with refractory brick 3. Throughout the zone of maximum abrasion and heat, extending generally about 105 20 feet above the bosh, I have shown the lin- 110

ing as having disappeared and been replaced by a thin agglomerate lining 4 adhering to the jacket wall. This correctly illustrates the physical condition of a furnace which was 5 treated according to my process and follows. A plurality of bronze bosh blocks 5 of the standard type cored for water circulation were provided and for each block an individual mounting frame 6 was used, this frame 10 having its body portion curved to conform to the curvature of the jacket, and having also a slightly tapered inturned flange 7 surrounding the opening in the frame and adapted to receive the block with a snug, gas tight 15 fit when driven home therein. The jacket has an opening 8 cut therein to receive the flange 7. The frame will overlie the jacket about the opening 8 therein sufficiently to receive attaching means to connect it to the 20 jacket. Preferably bolts 9 are used, these being inserted after the frame was mounted in the jacket opening by passing the threaded ends of the bolts outwardly through the jacket and frame and applying nuts to detachably mount the frame with a gas tight 25 joint on the jacket. The cooling blocks are then driven home in their respective frames and when in place are connected up in series by water supply pipes 10, each at one end con- 30 nected to the inlet nipple 11 at one side of a block and at the other end connected to the outlet nipple 12 of an adjacent block. The blocks as thus mounted in the furnace can be connected up in any suitable manner with 35 each other and with a source of cooling water.

The blocks are to be introduced in the furnace in such relative positions as will produce the results in view. If used to treat a small hot spot, they should be located in 40 such relation thereto that the agglomeration of stock, as indicated at 13 thereon, would gradually fill out the worn or missing portion of the lining at the hot spot. If an entire zone is to be lined or relined the blocks should 45 be arranged at different levels and staggered, the spacings between the blocks being such that they would cause an agglomeration to extend sufficiently to overlap from block to block. In practice I found this to occur sat- 50 isfactorily where the blocks on a given level were spaced on three foot centers and the lines were spaced about five feet. When so ar- 55 ranged it was found that within a very short time there had agglomerated or built up on and around the blocks a lining of semi-refrac- 60 tory material composed of particles of ore, ashes, silica, graphite, coke and alumina. The lining thus formed was very hard, and as cooled by the embedded blocks, was sufficient- 65 ly refractory to withstand the furnace tempera- tures. I found by removing a bosh block for inspection that this agglomerate lining ex- 70 tended over its inner end, thus materially pro- 75 tecting it from abrasion at that point, and that the agglomerated lining had built up as well

under as over the blocks, it evidently being the case that a gradual accumulation of the semi-molten stock would build up through- 70 out the zone cooled by the blocks until all of the jacket was covered and all of the blocks were entirely embedded in such agglomerate lining.

In a furnace which for 20 feet above its bosh was entirely devoid of brick lining I succeeded, by the placing of cooling blocks in the manner described, in building up an ag- 75 glomerated replacement lining in a very short time, and from careful inspections and tests of this lining there is no evidence of any de- 80 terioration in it at all, apparently there being a gradual replacement of the lining as it is worn by abrasion. This would seem to re- 85 sult from the fact that throughout the entire zone in which the cooling effect of the block is appreciable there will be no diminution of this agglomerated lining. In the event any 90 of the blocks should fail for any reason, it is a very simple and inexpensive matter to unbolt its respective mounting frame, disconnect its pipes 10 and take out the frame and block 95 for inspection, if necessary shutting off the blast temporarily. The block can thus be readily inspected, a new block substituted, and its mounting frame remounted in the jacket. It will be noted that the jacket di- 100 rectly supports the frame and block because the flange 6 will rest on the bottom of the jacket opening 8.

It is one of the most important features 100 of my invention that the frames will permit the blocks to be very readily mounted with a gas tight joint in the furnace while making it simple to remove and replace them. It is important that these cooling blocks be mount- 105 ed firmly so as to carry the entire weight of lining, as expansion under operating condi- 110 tions may throw the entire weight of lining on the cooling blocks.

Having thus described my invention, what 110 I claim as new and desire to secure by Let- 115 ters Patent, is:

1. The hereindescribed process, which con- 115 sists in utilizing water cooled projections ex- 120 posed to the stock in a furnace to cause an ag- 125 glomerate composite lining of stock particles to cohere to and build up about them until a lining is formed.

2. The hereindescribed process for lining 120 a furnace, which consists in causing an ag- 125 glomerate mass of stock comprising molten and semi-molten particles to take hold upon water cooled parts and build itself up into a lining for the furnace.

3. The hereindescribed process for replac- 125 ing the lining of a furnace jacket, which con- 130 sists in mounting one or more water cooled blocks to project into the space formerly occu- 135 pied by the lining to be replaced and to collect about their overhung inner ends a com- 140 posite agglomerate lining of stock materials

which ultimately embed the block and protect it.

4. The hereindescribed process for creating a lining within the jackets of blast furnaces and the like, which consists in mounting water cooled blocks to project substantially inwardly beyond the furnace walls so that an agglomeration of stock material will accumulate on and about said blocks, and 10 spacing said blocks on centers to produce cooled zones which overlap throughout the space to be lined.

5. The process of producing a lining for the metal jacketed wall of a blast furnace 15 stack which comprises providing cooling elements to contact with the furnace stock and chill and agglomerate particles thereof immediate thereto.

6. The process of producing a lining for 20 the metal jacketed wall of a blast furnace

stack which comprises providing cooling elements within the metal jacket adjacent the inner periphery thereof to contact with and agglomerate heated particles of furnace stock immediate thereto.

7. The process of producing an agglomerate lining within the metal jacketed wall of a blast furnace stack which comprises chilling the heated descending stock in the furnace adjacent said metal jacket.

8. The process of producing a lining within the metal jacketed wall of a blast furnace stack which comprises chilling the heated descending stock in the furnace at a plurality of points adjacent said metal jacket to agglomerate particles of the stock in areas immediate said points, said areas overlapping to produce a solid lining.

In testimony whereof I affix my signature.

JAMES P. DOVEL.
